(57) **CLAIM**

The ornamental design for an electronic payment terminal, as shown and described.

DESCRIPTION

FIG. 1 is a perspective view of an electronic payment terminal showing my new design;

FIG. 2 is a front view of the electronic payment terminal;

FIG. 3 is a rear view of the electronic payment terminal;

FIG. 4 is a left side view of the electronic payment terminal;

FIG. 5 is a right side view of the electronic payment terminal;

FIG. 6 is a top plan view of the electronic payment terminal; and,

FIG. 7 is a bottom plan view of the electronic payment terminal.

Various suitable materials can be used for the electronic payment terminal. For example, the electronic payment terminal can include an electronic signature pad. In some implementations, the body of the electronic payment terminal can be made by using various suitable materials, including, e.g., metals, plastics, or the combination of the metals and the plastics. The electronic signature pad can be made by using various suitable materials, including, e.g., glass or plastics.
